UNITED STATES PATENT OFFICE.

BAYARD D. KUNKLE, OF WILKINSBURG, PENNSYLVANIA, ASSIGNOR TO WESTINGHOUSE ELECTRIC AND MANUFACTURING COMPANY, A CORPORATION OF PENNSYLVANIA.

STARTING MECHANISM FOR AUTOMOBILES.

Application filed April 6, 1915. Serial No. 19,480.

To all whom it may concern:

Be it known that I, BAYARD D. KUNKLE, a citizen of the United States, and a resident of Wilkinsburg, in the county of Allegheny and State of Pennsylvania, have invented a new and useful Improvement in Starting Mechanism for Automobiles, of which the following is a specification.

My invention relates to starting mechanisms for automobiles and particularly to such mechanisms as embody a shiftable pinion for effecting the operative connection of starting motors to the engine shafts of automobiles or other motor vehicles.

My invention has for its object to provide a simple and efficient means whereby the operative connection of a starting motor to the shaft of an internal combustion engine may be automatically controlled in accordance with the energy supplied to the motor.

Starting devices embodying a longitudinally shiftable pinion which coacts with a gear wheel for establishing the operative connection of the motor to the engine shaft have been proposed heretofore. They possess certain disadvantages, however, in that the motor has acquired a considerable degree of speed when the gear wheels are brought into engagement. The meshing of the gear wheels is rendered difficult, not only because of their relative angular movements, but because of the lateral pressure between the sides of the coacting teeth.

According to the present invention, a longitudinally slidable pinion is loosely mounted on the motor shaft. When energy is supplied to the motor, the pinion is shifted into engagement with a coacting gear wheel and, at the same time, the pinion is connected to the motor shaft for rotation therewith.

The details of my invention will be described in connection with the accompanying drawings, in which Fig. 1 is a side view, partially in elevation and partially in section, of a starting mechanism constructed in accordance with my invention. Fig. 2 is a view, similar to Fig. 1, of a modification. Fig. 3 is a diagrammatic view of circuits and apparatus employed in the arrangement of Fig. 2.

Referring particularly to Fig. 1, an engine fly wheel 1, only a portion of which is

shown, is provided with gear teeth 2. An electric motor 3 is provided with a field magnet frame 4 having any suitable number of poles, only two of which are shown. The motor has an armature shaft 5 which is provided with a radially projecting pin 6. A pinion 7 having a smooth bore fitting the plain shaft 5 is loosely and slidably mounted on the shaft 5, and is provided with a clutch member 8 having a projecting member 9 or inclined jaw for engaging the pin 6.

The position of the pinion 7, relatively to the shaft 5, is controlled by a lever 10 that is pivotally mounted on a lug 11 that may be integral with the field-magnet frame 4. The lever 10 is provided with a rearwardly projecting arm 12 which extends adjacent to the field-magnet frame and is adapted to be drawn toward the frame by magnetic force when the latter is energized by the field-magnet windings. A spring 13 serves to normally maintain the lever 10 and the pinion 7 in their respective illustrated positions. A housing 14 encloses the pinion 7 and the outer end of the armature shaft 5 and provides a bearing for the latter at its outer end.

It may be assumed that the various parts are in their respective illustrated positions, with the pinion 7 out of engagement with the gear teeth 2. To start the engine, the circuit of the motor may be completed by any suitable electrical means (not shown). When the motor windings are energized, the field magnet frame 4 exerts a magnetic pull on the arm 12 which is sufficient to actuate the lever 10 against the tension of the spring 13. The motor rotates in a counter-clockwise direction, as viewed from the right in Fig. 1. The pinion 7 is actuated longitudinally on the shaft 5 into mesh with the gear wheel 2. The pin 6, which is carried by the rapidly rotating shaft 5, engages the inner inclined surface of the clutch jaw 9 and the pinion will be drawn completely into mesh by the cam action of these coacting parts. The fly wheel 1 is then rotated to crank the engine.

When the engine starts under its own power, the pinion 7 will be driven at a speed greater than that of the motor shaft and the pinion will, accordingly, be caused to overrun the shaft. The relative motion of these

parts operates, by reason of the cam action of the pin 6 upon the inner inclined surface of the slot in the clutch member 8 and the outer inclined surface of the jaw 9, to shift the pinion to the left, out of engagement with the gear teeth 2.

The disengagement of the pinion from the fly wheel is insured by the action of the spring 13 which has been placed under tension when the gear wheels are in mesh. As soon as the engine starts under its own power, less current is required to operate the motor, and the energization of the field magnet poles will be correspondingly decreased. When the magnetic pull exerted upon the arm 12 is less than that exerted by the spring 13, the pinion 7 will be returned by the lever 10 to its normal position.

A modification of my invention is illustrated in Fig. 2, in which similar numerals are employed to designate corresponding parts. A pinion 15 is provided with a clutch member 8 for coacting with a pin 6 in the manner above described in connection with Fig. 1. The pinion 15 is further provided with a longitudinally extending sleeve member 16 which coacts with a reduced portion 17 of the motor shaft.

The pinion 15 and its connected parts are enclosed by a housing 18 which supports, at its outer end, an electromagnet 19. The electromagnet comprises a coil 20, that is in series with the windings of the motor 3, and a movable core member 21 that is rigidly connected to the sleeve member 16 of the pinion 15. A spring 22, that is interposed between the end of the reduced portion 17 and the end of the sleeve member 16, operates to normally retain the pinion 15 and the core member 21 in their respective illustrated positions.

An electrical circuit for controlling the mechanism of Fig. 2 is illustrated diagrammatically in Fig. 3. To start the motor, a switch 23 is closed to complete the motor circuit which extends from the ungrounded side of the battery through the magnet coil 20, the windings of the motor 3 to ground, and thence back to the battery. The motor then rotates in a clockwise direction, as viewed from the right in Fig. 2. The coil 20 is energized to actuate the core member 21 and the pinion 15 to the left to effect the engagement of the latter with the gear teeth 2. As above described in connection with Fig. 1, the force exerted upon the pinion 15 by the electromagnet 19, is supplemented by the cam action of the rapidly moving pin 6 and the clutch jaw 9.

When the engine starts under its own power, the pinion 15 overruns the motor shaft, and the relative movements of the clutch member 8 and the pin 6 serve to shift the pinion 15 to the right and out of engage-

ment with the gear teeth 2. Since the load of the motor is materially decreased upon the starting of the engine, a smaller current will traverse its circuit, and the magnet 19 will be de-energized to a corresponding degree. When the magnetic force exerted on the core member 21 is less than that of the spring 22, the latter will assist in actuating the pinion 15 and the connected parts to the right.

It will be noted that I provide a simple arrangement, whereby a shiftable pinion may be automatically actuated into and out of engagement with an engine member. There is no possibility of the pinion remaining in engagement with the engine fly wheel after the engine starts under its own power because of the cam action that is produced when the pinion overruns the motor shaft. In addition to this means for disengaging the gear wheels, the springs, which normally retain the pinion in an inoperative position, assist in effecting the disengagement of the connected parts when the opposing magnetic force exerted by the controlling means is less than that of the springs.

I claim as my invention:

1. In a starting mechanism, the combination with an engine member, and a motor having a shaft provided with an engaging member, of a gear member loosely mounted on said shaft, and having a plurality of inclined portions extending laterally therefrom for coacting with said engaging member to shift the driving member in opposite directions according as the motor constitutes the driving or the driven member, and means for controlling said gear member.

2. In a starting mechanism, the combination with an engine member and an electric motor having a shaft, of a driving member loosely mounted on said shaft, means comprising a coil in series with said motor for initiating the operative connection of said driving motor to said engine member and to said shaft substantially simultaneously, and auxiliary means for assisting said first mentioned means to connect the driving member to said engine member and for rendering said connection inoperative when the engine member has been started.

3. In a starting mechanism, the combination with an engine member and an electric motor having a driving shaft, of a pinion loosely mounted on said shaft, electro-responsive means in series with said motor for effecting the operative connection of said pinion to said engine member and to said shaft, and automatic means for assisting said electro-responsive means to connect the pinion to the engine member and for rendering said operative connection ineffective when said engine member has been started.

4. In a starting mechanism, the combina-

- tion with an engine member, and a motor having a shaft, of a gear member mounted on said shaft and having a plurality of inclined portions, electromagnetic means for initiating the operative connection between said engine member and the gear member, and an engaging member on said shaft for co-acting with one of said inclined portions to assist in effecting connection between the engine member and the gear member and for co-acting with a second inclined surface to withdraw the gear member from operative connection with the engine member when the engine member has been started.
- 5 5. In a starting mechanism, the combination with an engine-driven gear, of a motor having a substantially plain shaft, a pinion mounted on said shaft having a substantially smooth bore and slidable freely longitudinally and rotatably thereof, and means for moving said pinion into, and out of, operative relation with said shaft and gear while the motor is rotating, said means comprising co-operating devices on the motor shaft and 20 on the pinion for advancing the pinion into meshing relation with said gear and coupling it to the shaft to crank the engine, and for uncoupling the pinion from the shaft and withdrawing it from its meshing relation after the engine has been cranked.
- 10 6. In a starting mechanism, the combination with an engine-driven gear, of a motor having a substantially plain shaft, a pinion mounted on said shaft having a substantially smooth bore and slidable freely longitudinally and rotatably of said shaft, means for moving said pinion into, and out of, operative relation with said shaft and gear while the motor shaft is rotating, said means comprising co-operating devices on the motor shaft and on the pinion for simultaneously advancing the pinion into meshing relation with said gear and coupling it to the shaft to crank the engine, and for simultaneously uncoupling the pinion from the shaft and withdrawing it from its meshing relation after the engine has been cranked, and resilient means co-operating with said devices during said coupling and uncoupling operations.
- 15 7. In an engine starter, the combination with an engine member, a motor, a shaft rotated by said motor, and a driving member mounted on said shaft, of means for moving said driving member into driving engagement with said engine member, said means comprising an electromagnetic device, and a device rigidly mounted upon said shaft and co-acting with said driving member.
- 20 8. In an engine starter, the combination with a member connected to the engine, a motor, a plain shaft rotated by said motor, and a driving member mounted upon said shaft and adapted to engage and operate said engine member but normally out of engagement therewith, of means for causing the driving member to slide longitudinally with respect to said shaft, and auxiliary means for assisting the movement of said driving member into engagement with said engine member and for effecting driving connection between the motor and driving member.
- 25 9. In an engine starter, the combination with an engine member, a motor, a plain shaft rotated by said motor, a driving member mounted upon said shaft, and means on said driving member to engage with and operate the engine member but normally out of engagement therewith, of means for moving said driving member into engagement with the engine member, and auxiliary means operated by the rotation of the armature shaft for assisting the movement of the driving member into engagement with the engine member and for effecting a positive clutch connection between the motor and the driving member, said auxiliary means also serving to automatically withdraw the driving member from such engagement when the engine runs on its own power.
- 30 10. In an engine starter, the combination with a member operatively connected with the engine, an electric motor having a plain shaft extension, a driving member mounted on said shaft and adapted to drive the engine member but normally out of engagement therewith, means for initiating movement of the driving member to effect connection between the engine member and the driving member, and auxiliary means mounted on the driving member for engaging the shaft whereby operation of the motor assists in advancing the driving member into engagement with the engine member.
- 35 11. In an engine starter, the combination with an engine member having teeth thereon, an electric motor having an extended armature shaft, a pinion mounted thereon for longitudinal and partial rotary movements relative thereto and adapted to mesh with the teeth on said engine member, means for initiating the movement of said pinion into mesh with said teeth, and auxiliary means controlled by the rotation of the shaft for assisting in advancing the pinion into mesh with said member, the subsequent rotation of said engine member, which exceeds that of the shaft, withdrawing the pinion from mesh with the teeth of the engine member.
- 40 12. An engine starter comprising, in combination with a member operatively connected with the engine, a motor, a plain shaft operated by said motor, a driving member having a smooth bore therein and

being mounted upon the motor-operated shaft, said driving member being adapted to slide longitudinally upon said shaft into and out of engagement with said engine member, and means co-operating with the rotation of said motor to cause the driving member to move into engagement with the engine member, said means serving to release the driving member from such engagement when the engine runs on its own power.

In testimony whereof, I have hereunto subscribed my name this 30th day of March 1915.

BAYARD D. KUNKLE.
